UNITED STATES PATENT OFFICE.

ATWELL J. BLACKFORD, OF CLEVELAND, OHIO, ASSIGNOR TO AMERICAN STOVE COMPANY, OF ST. LOUIS, MISSOURI, A CORPORATION OF NEW JERSEY.

WICK BLUE-FLAME OIL-BURNER.

1,074,687.

Specification of Letters Patent.

Patented Oct. 7, 1913.

Application filed November 12, 1912. Serial No. 730,986.

To all whom it may concern:

Be it known that I, ATWELL J. BLACKFORD, a citizen of the United States, residing at Cleveland, in the county of Cuyahoga and State of Ohio, have invented certain new and useful Improvements in Wick Blue-Flame Oil-Burners, of which the following is a specification, reference being had therein to the accompanying drawing.

10 This invention relates to improvements in wick blue-flame oil burners, and is of that type in which there is an initial heating oil flame; a vapor generating blue flame which is generating an excess of vapor and which 15 is fed to the blue-flame burner-cap to be burned for cooking purposes.

The present invention is an improvement upon the burner shown in my co-pending application, Serial No. 730,985, filed November 12th, 1912, and the objects of the improvement are: 1st. To provide means for preventing the outward flow of vapor through the lighting or match opening of the burner. 2nd. To cause the excess vapor 25 to pass through a perforated flange in the cap or deflector of the generator burner, and 3rd. To so construct the parts that the yellow initial heating flame cannot be inadvertently left burning.

30 In the accompanying drawings Figure 1 is a perspective view of a burner embodying my present improvement. Fig. 2 is a detached perspective view of the vertically movable draft tube. Fig. 3 is a central vertical sectional view through a burner embodying my present improvement. Fig. 4 is a top plan view of my improved burner cap or deflector.

Referring now to the drawings, 1 indicates a chimney and 2 a wick-tube projecting up in the lower end of the chimney. A vertically movable wick 3 is within the wick-tube 2 and vertically adjustable through the medium of any desired form 45 of wick-raising device 4. A burner-cap or deflector 5 is provided with radially projecting arms 6, adapted to rest upon the upper end of the wick and movable therewith upon a rod 6, the upper end of the rod having a nut 7 which limits the upward movement of the wick and deflector 5. Projecting outward over the arms 6 is an annular flange 8, provided with two rows of openings 9. This flange 8 is surmounted by an inverted cup-shaped member or flange 10,

with its edge apart from the flange 8, as clearly shown in Fig. 3. Surrounding the upper end of the wick-tube and the cap 5 is a vertically arranged perforated annular wall 11, which is connected with the lower 60 enlarged end 12 of the chimney 1, by a depending apron 13, which has its lower end resting within the vertical wall of a cup-shaped flange 14, the horizontal wall of the member 14 being provided with openings 65 15. The lower edge of the perforated wall 11 rests in a cup-shaped flange 16, which supports and centers the wall 11, the chimney and parts that are connected with the perforated wall 11.

70 Located within the chimney 1 is a vertically arranged tube 17, having open ends, the upper open end being located under a slotted blue-flame burner-cap 18, which latter is located at the top and upper end of 75 the chimney 1. This tube 17 is movable vertically to the position shown in dotted lines Fig. 3, and when elevated the wick 3 is lighted by passing a match through the lighting openings 19, 20 and 21, and when 80 in this raised position, the burner burns with a yellow flame. This yellow flame is utilized to heat the tube 17, chimney 1 and the burner 18 sufficiently to prevent a condensation of the vapors within the tube 17 85 and thereby prevent the accumulation of a tarry substance on the inner side of the tube 17. This tube is raised to the position shown in dotted lines through the medium 90 of an intermediate pivoted lever 22, which has its inner end pivotally connected to the tube 17 at the point 23, the outer end of the lever carrying a handle 24, the pivotal point 25 of the lever is upon the enlarged portion 12 of the chimney 1, and the lever passes 95 through a slot 26 therein. Heretofore in this type of burner, means has been provided for locking the tube 17 in its upper position and this has been found undesirable and faulty, because the operator is liable to leave the burner with the yellow flame longer than necessary and thus permit it to become over heated, which over heating accelerates the flame to still greater overheating, and this action continues in increased proportion 100 until there is a liability of a dangerous fire. In this improvement it is necessary for the operator to hold the tube up until the parts of the burner have become sufficiently heated 105 and it cannot be left inadvertently with the 110

yellow flame. A releasing of the handle 25 releases the tube and it assumes the position shown in Fig. 3. In this position a small blue-flame is the result, which is not subject 5 to the above faulty result.

The operation of this improvement is as follows: The handle 24 is depressed and the tube 17 lifted. The wick is then lighted as before described. This tube is held in the 10 elevated position until the parts of the burner have become sufficiently heated for the final operation. When the handle is released, the tube automatically falls to the position shown in Fig. 3, with its lower enlarged or flared 15 end 27 fitting closely the periphery of the flange 8. This converts the yellow flame into a blue flame, which is termed a vapor generating blue-flame. This blue flame generates more vapor than is required for the generating blue-flame, and the draft caused by 20 the tube 17 draws the excess vapor through the openings 9 in the flange 8 into the tube 17. To accelerate the draft a series of openings 25 28 are provided in the tube 17, just above the cap 5. This excess vapor with the air mixed therewith passes through the tube 17 and is delivered to the slotted blue-flame burner-cap 18, where it is lighted and a blue flame of considerable extent and maximum 30 heating capacity is the result.

I have found that in the operation of a burner of this type, there is a tendency to a leakage of the vapor through the lighting opening 19, 20 and 21, causing a disagreeable odor. This defect I have overcome by 35 providing the tube 17, with a slot or opening 29 located in the opposite side of the tube 17 and above the burner cap 5. I find that by admitting air to the tube 17 at this point, 40 the draft is so increased and the result is such that there is no escape of vapor or odor through the lighting openings.

It will be observed that all the excess vapor is caused to pass through the perforated 45 flange 8 by reason of the lower end of the tube 17 fitting the flange tightly. This causes a strong draft through these openings at the point of the blue flame and effectively draws the excess vapor from the flame and 50 from points adjacent the flame, which robs

the flame and causes a reduced flame and provides an excess amount of unburned vapor of an amount sufficient to supply the burner-cap at the top of the chimney 1.

Having thus described my invention, what 55 I claim and desire to secure by Letters Patent is:

1. A burner of the type described, comprising a chimney having at its upper end a blue-flame burner cap, a burner within the 60 lower end of the chimney, said burner having a cap with a perforated flange, a vertically movable tube within the chimney adapted to convert the flame of the burner from a yellow to a blue flame, manually 65 operated means for lifting the tube constructed to cause the tube to automatically fall when the manually operated means is released and thus automatically cause the conversion of the yellow flame into a blue 70 flame for the purpose described.

2. A burner of the type described, comprising a chimney having a blue-flame burner cap at its upper end, a wick burner within its lower end, a cap for the wick 75 burner having a perforated annular flange, a vertically movable tube within the chimney, the lower end of the tube adapted to fit snugly the periphery of the said flange to cause the excess vapor to be drawn through 80 the said perforations of the flange and the draft therethrough increased, for the purpose described.

3. A burner of the type described, comprising a chimney having a blue-flame 85 burner-cap at its upper end, a wick-burner at its lower end, a cap for the said wick burner, a vertically movable tube adapted to coact with the cap to produce a blue flame, the chimney and parts adjacent the wick 90 having registering lighting openings, and the tube having an air opening above the burner-cap and on the side opposite the said lighting openings for the purpose described.

In testimony whereof I hereunto affix my 95 signature in the presence of two witnesses.

ATWELL J. BLACKFORD.
